UNITED STATES PATENT OFFICE

CHARLES McNEIL, OF GLASGOW, SCOTLAND

HEAT EXCHANGING DEVICE

Application filed December 11, 1928, Serial No. 325,362, and in Great Britain July 11, 1928.

This invention relates to heat-exchanging devices for incorporation, for example, in evaporators and crystallizers of the type including a drum or otherwise shaped containing vessel and a tubular structure rotatable within the vessel.

In the device according to the invention the rotatable structure comprises a main pipe, which may be continuous or interrupted, journaled in the vessel and carrying near each end of the vessel a hollow spider in the form of tubular arms disposed radially of the main pipe and integral with or detachably mounted on a box or the like carried by, and open to the interior of, said pipe, said arms being interconnected or not by stays at or near the periphery, and banks of preferably straight parallel tubes extending lengthwise of the vessel and interposed between co-related arms of the hollow spiders, through which banks either heating or cooling fluid is caused to pass, the fluid entering at one end of the main pipe, traversing the box at that end, passing thence through the set of hollow radial arms at that end, along the banks of longitudinal tubes, through the second set of radial arms, through the second box, and through the opposed end of the main pipe.

Each element comprising a pair of arms and connecting longitudinal tubes may have independent connections to the main pipe.

A heat-exchanging device according to the invention is illustrated by way of example in the accompanying drawing in which Fig. 1 is a central vertical section and Fig. 2 a transverse section on the line 2—2 of Fig. 1.

Referring to the drawing, 1 denotes a cylindrical drum or vessel within which is rotatable a tubular structure including radially disposed banks of straight parallelly arranged tubes 2 extending lengthwise of the vessel between co-related tubular spider arms 3 constituting headers. The said spider arms 3 radiate from boxes 4, 5 integral with hollow trunnions 6, 7 journaled in bearings 8, 9 sustained by the end plates 10, 11 and rigidly interconnected by a pipe 12 coaxial with the trunnions 6, 7.

The box 4 constitutes a single distribution chamber communicating with all of the head-

ers 3 radiating therefrom. The box 5 is subdivided by radial partitions 13 into eight compartments 14 each communicating with a header 3 and each having an outlet port 15 opening into the hollow trunnion 7.

16 denotes internal ferrules fitted into the inlet ends of the tubes 2.

The construction illustrated is adapted for use with steam as the heating fluid to be passed through the tubes 2.

In operation, steam enters the hollow trunnion 6 and passes by way of the box 4 into the headers 3 radiating therefrom, along the banks of tubes 2 into the headers radiating from the box 5, into the compartments 14, and outwardly through the ports 15 into the hollow trunnion 7.

The ferrules 16 in the inlet ends of the tubes 2 serve to prevent any condensate in the tubes 2 from passing backwardly into the box 4. As the elements attain their highest position the condensate in the tubes 2 flows into the box 5 whence it passes to the hollow trunnion 7 by way of the ports 15, reflux flow of the condensate being impossible due to the construction of the box 5.

The tubular structure may be rotated in any convenient manner, and the vessel may be subjected to vacuum.

The containing vessel is provided with inlet and outlet openings (not shown).

What I claim is:—

In combination with a liquid-containing vessel, coaxial fluid inlet and outlet connections and a structure in communication with said connections and rotatable around the axis of said connections, said structure comprising a box connected to the fluid inlet connection, a box connected to the fluid outlet connection, a set of headers radiating from each box, banks of tubes connecting said sets of headers, internal ferrules at the ends of the tubes adjacent to the first box and partitions subdividing the second box into compartments, one compartment for each header connected to that box.

In testimony whereof I have signed my name to this specification.

CHARLES McNEIL. 100
